(57) **CLAIM**

The ornamental design for a hinge for furniture, as shown and described.

DESCRIPTION

FIG. 1 is a perspective view of the hinge for furniture according to the invention;

FIG. 2 is a left side elevation view of the hinge for furniture of FIG. 1;

FIG. 3 is a right side elevation view of the hinge for furniture of FIG. 1;

FIG. 4 is a top plan view of the hinge for furniture of FIG. 1;

FIG. 5 is a bottom plan view of the hinge for furniture of FIG. 1;

FIG. 6 is a front elevation view of the hinge for furniture of FIG. 1;

FIG. 7 is a rear elevation view of the hinge for furniture of FIG. 1;

FIG. 8 is a cross-sectional view of the hinge for furniture through line 8-8 shown in FIG. 4;

FIG. 9 is a cross-sectional view of the hinge for furniture through line 9-9 shown in FIG. 3;

FIG. 10 is a left side elevation view of the hinge for furniture according to the invention in a state where the hinge for furniture is closed; and,

FIG. 11 is a perspective view of the hinge for furniture according to the invention in a state where a metal pedestal is attached.

The broken line showing of the hinge for furniture is for the purpose of illustrating the environmental structure and forms no part of the claimed design.

1 Claim, 5 Drawing Sheets
